UNITED STATES PATENT OFFICE.

ALEXANDER S. BAIRD, OF NEW YORK, N. Y.

DESIGN FOR A DRUGGIST'S LABEL-CASE.

SPECIFICATION forming part of Design No. 35,468, dated December 24, 1901.

Application filed September 27, 1901. Serial No. 76,808. Term of patent 14 years.

To all whom it may concern:

Be it known that I, ALEXANDER S. BAIRD, a citizen of the United States, and a resident of the city of New York, borough of Manhattan, in the county and State of New York, have invented and produced a new and original Design for a Druggist's Label-Case, of which the following is a specification, reference being had to the accompanying drawings, forming a part thereof, in which—

The leading feature of the design consists in the formation of the body of the case, in which single opposing transverse members A appear, secured to a side member B, as well as longitudinal side members C and C', one of the latter members C being continuous with the transverse members, while the opposing longitudinal member appears in two sections c and c', extending one below the other, the upper section c having an opening

D therein, while the other or inner member c' diverges at its front end and terminates in an enlargement D'.

The minor features of the design consist in the lugs E, which appear extending from the body of the case, and in the post element F, which is carried out from the side member B, together with the horizontal member d, which extends within the case from the upper wall of an opening D² in the said member B of the body.

Having thus described my invention, I claim as new and desire to secure by Letters Patent—

The design for a label-case herein shown and described.

In testimony whereof I have signed my name to this specification in the presence of two subscribing witnesses.

ALEXANDER S. BAIRD.
